CLAIM

The ornamental design for a watch for mounting on a surfboard leash, as shown and described.

DESCRIPTION

FIG. 1 is a left side isometric view of the watch for mounting on a surfboard leash, shown mounted on a typical surfboard leash, in accordance with my new design;

FIG. 2 is an enlarged isometric view of the watch for mounting on a surfboard leash, taken from the left side;

FIG. 3 is an enlarged isometric view thereof, taken from the right side;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front elevation view thereof; and,

FIG. 9 is a rear elevation view thereof.

The portions of the watch for mounting on a surfboard leash shown in broken lines form no part of the claimed design. The broken lines showing the surfboard leash illustrate environmental structure only, and form no part of the claimed design.
